INTERNAL COMBUSTION ENGINE

Edwin S. Hall, New Haven, Conn.

Application March 23, 1936, Serial No. 70,216

6 Claims. (Cl. 123—58)

This invention relates to internal combustion engines, and has for its main object the provision of an opposed-piston engine of unusually compact form and simple construction. This object is attained by using the "barrel engine" cylinder arrangement, the cylinders being parallel to the shaft, with two coaxial reciprocating-rotary engine mechanisms whose piston members have pistons operable in the same set of cylinders.

10 Ordinarily in opposed-piston barrel engines, two engine mechanisms are mounted on the same rather long shaft; the opposed piston thrusts tend to bend the shaft, and may cause early fracture. An object of this invention is to avoid this difficulty by mounting the two reciprocating-rotary engine mechanisms independently, each with a short shaft on its own journal and thrust bearings in the engine casing members, so that the tensile and bending loads between the ends 20 of the engine arising from the opposed piston thrusts, are carried by the fixed members of the engine which are naturally well adapted to carry such loads without appreciable deflection.

Another object of this invention is to provide, 25 in an opposed-piston barrel engine, cylinders having intake ports toward one end and exhaust ports toward the other end, constructed and arranged so that all of the ports can be accurately located, of ideal form, and readily machined, and so that the intake ports of the several cylinders can be fed from a common wind- 30 chest to insure uniform distribution of the air, while the exhaust ports discharge into separate exhaust elbows to prevent the exhaust of one cylinder from blowing into the ports of adjacent cylinders. A further object is to provide sure 35 and adequate cooling to all port bridges. These objects are attained by providing individual cylinder units each having its own annular water jacket thru which the ports extend more or less radially, with axial water passages thru the port bridges. These cylinder units extend thru a common windchest casing member, and thru individual exhaust elbows, and are bolted between 40 two engine casing members having chambers for the cooling fluid forming manifolds connecting the ends of the several cylinder jackets. Axial flow of the cooling fluid thru the cylinder jackets and thru the port bridges can be maintained by 45 pumping the fluid into the chamber of one of the engine casing members while permitting it to flow out of the other, suitable radiator means being included in the circuit as usual.

In an opposed-piston engine, the pistons which 50 uncover the exhaust ports run hotter than those

which control the intake ports, and in the absence of any special cooling means within the pistons, the size of the exhaust pistons is limited by their ability to stay cool enough, while the intake pistons can be somewhat larger without 5 running any hotter. It is advantageous, therefore, with the object of getting the most displacement into a given engine bulk, to make the exhaust pistons somewhat smaller in diameter than the intake pistons, and a secondary advantage is the ability to take more intercylinder room between adjacent exhaust cylinders to accommodate the individual exhaust outlet members and provide for free flow of the exhaust from the inner sides of the cylinders. 10

Another object of the invention is to provide for reasonably tight connections between the several exhaust outlets and the exhaust manifold, in spite of heat stresses, by leaving each individual elbow some slight freedom to swivel about 20 its cylinder with suitable ring packing, and by having all manifold gaskets in a common plane.

Other objects of this invention are to provide adequate and efficient reciprocating-rotary engine mechanisms for an opposed-piston barrel 25 engine. In discussing barrel engine mechanisms, it is convenient to distinguish between a "swashplate" and a "wabbler." Both are platelike structures inclined to the shaft and concentric with the shaft. In the following, it will be understood that a "swashplate" rotates with the shaft, being fixed thereon, while a "wabbler" does not rotate with the shaft, being mounted on bearings on the shaft, the axis of the bearings being inclined to the axis of the shaft. In some wabbler mechanisms, the wabbler is mounted on a Z-crankshaft; in others, the wabbler is mounted upon a swashplate. 30

In barrel engine mechanisms, particularly of the opposed-piston type, efficient and fully satisfactory means for taking the torque reaction from the operation of the reciprocating-rotary engine mechanisms have not been easy to provide. By the use of suitable wabbler mechanisms, the torque reaction can be made to appear as 45 side thrust of the piston members, and an object of this invention is to provide in an opposed-piston engine, cylindrical guide surfaces for the piston members, coaxial with the cylinders and extending longitudinally across the wabbler case, 50 so that the side thrust of the piston members can be carried efficiently by well-lubricated surfaces in line with the direction of the thrust and without subjecting the piston members to bending loads. This construction is the mechanical 55

equivalent of the crosshead in crank engines, but is without the complication and added bulk usually associated with crosshead construction. A further object is to provide improved accessibility in an opposed-piston barrel engine, whereby the piston members and their operable connections with the wabbler may be readily assembled and removed.

These and other objects of the invention may be more completely understood from the following description in connection with the drawings in which:

Fig. 1 is a longitudinal sectional view of the forward portion of the engine, taken substantially on the line A—A of Fig. 3;

Fig. 2 is a longitudinal sectional view of the after portion of the engine, taken substantially on the line A—A of Fig. 3; and

Fig. 3 is a partial transverse sectional view of the engine, taken on the line 3—3 of Fig. 1.

Fig. 4 is a partial transverse sectional view, taken on the line 4—4 of Fig. 2.

Fig. 5 is a partial transverse sectional view, taken on the line 5—5 of Fig. 2.

Referring to the drawings, hollow shaft 10 is mounted in journal bearings 11 in casing 20 and casing cover 21, and is located axially by pivoted slipper thrust bearing 12. Instead of the plain and slipper bearings shown, anti-friction bearings could be used if desired. Splined on shaft 10 is swashplate member 13 having plane working faces and a spherical central boss. The spherical boss provides a substantial means for mounting the swashplate on shaft 10, and makes possible easy machining of swashplate member 13 since all its exterior surfaces are surfaces of revolution relative to the swashplate axis, while the splined hole thru the hub is easily machinable relative to the axis of the hole, the two axes intersecting at the center of the spherical boss.

The spherical boss also forms a self-aligning pilot member for wabbler 30, which is composed of two similar portions bolted together about swashplate 13. Wabbler 30 has bearing elements coaxing with the plane working faces and spherical pilot boss surfaces of swashplate 13. These bearing elements may be plain bearing surfaces conforming to the surfaces of swashplate 13, or slipper elements such as slippers 31 pivoted in wabbler 30 and having working faces to coat with the surfaces of swashplate 13. Wabbler 30 is substantially U-shaped in section, and is fed with oil thru holes 14 in swashplate 13, the centrifugal action of the swashplate maintaining wabbler 30 full of oil during operation. Oil holes 14 lead oil from within shaft 10 to the points on swashplate 13 that are normally either not loaded or carrying less load than the other parts of swashplate 13. Slippers 31 are shown on one side only of swashplate member 13, with plain bearings on the other side. Slippers could be provided on both sides, and on the spherical pilot surface also, or they could be omitted entirely and plain bearings used if desired.

Wabbler 30 has arms 33 attached thereto by screws 32. Each arm 33 is provided with a cylindrical bore 34 whose axis is substantially in the mid-plane of and tangent to a circle concentric with wabbler 30. Pin 35, a free fit in cylindrical bore 34 of arm 33, is carried by crosshead 36 which is a free fit in a cylindrical bore 41 in piston member 40. Piston member 40 carries piston rings 43 slidable in cylinder 52 of cylinder member 50. The portion of piston member 40 in which is bore 41, is larger in diameter than the

piston proper, and has bearing shoes 42 freely fitting cylindrical guide surfaces 22 formed in casing 20 coaxial with cylinder 52.

The after reciprocating-rotary engine mechanism is similar to the forward mechanism just described. Hollow shaft 60 is mounted in journal bearings 61 in casing 70 and casing cover 71, and is located axially by pivoted slipper thrust bearing 62. The swashplate-wabbler construction is an inversion of that shown in Fig. 1. Swashplate members 63 are splined on shaft 60 and are spaced apart by spherical pilot member 65. Wabbler 80 is piloted on member 65 and lies between swashplate members 63. Plain bearing elements of wabbler 80 conform to the bearing surfaces of swashplate members 63 and pilot member 65, or slipper elements such as slippers 81 may be used if desired. Plates 88 with the rim section of wabbler 80 to which they are attached, form a U-shaped section to contain an oil bath for the bearing elements to work in, the centrifugal action of swashplate members 63 assisting in maintaining the oil bath within the U-sectioned ring of the wabbler.

Wabbler 80 has arms 83 attached thereto by screws 82. Each arm 83 is provided with a cylindrical bore 84 whose axis is substantially in the mid-plane of and tangent to a circle concentric with wabbler 80. Pin 85, a free fit in bore 84 of arm 83, is carried by crosshead 86 which is a free fit in cylindrical bore 91 in piston member 90, which carries piston rings 93 slidable in cylinder 53 of cylinder member 50. The portion of piston member 90 in which is bore 91, is larger in diameter than the piston proper, and has bearing shoes 92 freely fitting cylindrical guide surfaces 72 formed in casing 70 coaxial with cylinder 53.

Cylinder members 50 are individual units, each having an annular water jacket 51 and a belt of intake ports 54 and a belt of exhaust ports 55, the port bridges having axial water passages 56. Surrounding each cylinder member 50 is an individual exhaust elbow 25, having a flanged outlet bolted to exhaust manifold 26. All cylinder members 50 extend thru common windchest 74 formed in casing member 75. Cylinder members 50 pilot into holes in the inner ends of casing members 20 and 70, and are bolted to casing members 20 and 70 by bolts 21, between which water ports 57 communicate with water chambers 28 and 78 in casing members 20 and 70 respectively, these chambers 28 and 78 forming water manifolds connecting the water jackets 51 of the several cylinders 50. The same gaskets which seal the joint between the ends of water jackets 51 and casing members 20 and 70, also assist in sealing the joints between exhaust elbows 25 and casing 20, and casing member 75 and casing 70. Annular soft packing 58 is used to seal the inner ends of exhaust elbows 25 and casing member 75 relative to individual cylinder members 50. Casing member 75 extends forward around shaft 10 to form an oil tight sealed closure with casing member 20. During operation, cylinder members 50, being at higher temperature, expand more than the forward extension of casing 75. To take care of this condition, expansion joint 175 is provided between casing member 20 and casing member 75.

The common windchest 74 which supplies air to all intake ports 54, is connected by conduits 77 with a plurality of centrifugal blower units 79 mounted on the accessory assembly 97 at the rear of the engine. Conduits 77 could be formed integrally in casing 70 if desired.

Shaft 60 is keyed to bevel gear 17 meshing with one or more pinions 16 mounted in bearings in member 15 and adapted to drive various accessories thru radiating drive shafts 19. Shaft 68 is inserted thru shaft 60 and then thru shaft 10, and is driven by shafts 10 and 60 in any suitable manner compelling all three shafts to rotate together while permitting some misalignment of shafts 10 and 60 without deflection of shaft 68. Means should also be provided for convenient adjustment of the relative rotational position of shafts 10 and 60 in order to adjust the phase relationship of piston members 40 and 90. The means suggested comprises relatively short involute splines, fifteen splines 115 connecting shafts 10 and 68 and sixteen splines 116 connecting shafts 60 and 68, the vernier effect making possible adjustment of the rotational position of the shaft 10 relative to shaft 60 by increments of 1.5 degrees.

Fuel injection nozzles 59 are served by individual fuel pumps 39 which are operated by radiating push rods 38 and cam followers 37 which are driven by cam 18 fixed on shaft 10.

Casing member 20 has handholes 23 closed by covers 29, and cover 21 has handholes 24 closed by covers 49, to provide accessibility to pistons 40 and wabbler arms 33 and associated parts. Casing member 10 has handholes 73 closed by covers 81, and cover 71 has handholes 76 all of which are closed by the accessory assembly 97, to provide accessibility to pistons 90 and wabbler arms 83 and associated parts.

During assembly, the fuel injection system and accessory drive gears may be assembled in casing member 75, cylinders 50 inserted thru member 75, and casing member 10 bolted thereto by bolts 27. Then exhaust elbows 25 and casing member 20 can be assembled. The principal fixed parts of the engine are now formed as a rigid assembly having numerous advantageous features such as a common windchest to serve all intake ports, individual exhaust elbows which can be adjusted to line up properly and bolt tightly to manifold 26, and the possibility of axial flow of the cooling medium thru all cylinder watter jackets and port bridges. This construction also makes possible the complete machining of all cylinder ports, and is also more convenient in other ways than a mono-bloc construction in production. After shafts 10 and 60, with their thrust bearings, swashplate and wabbler members, and casing covers 21 and 71 have been assembled, piston members 40 and 90 may be inserted thru handholes 24 and 76 respectively, and wabbler arms 33 and 83, with their associated parts, may be inserted thru handholes 23 and 73 respectively, and fastened to wabbler 30 and 80 by screws 32 and 82 respectively. Obviously, the pistons and wabbler arm assemblies are easily accessible thru the handholes, for inspection and repair or replacement, without major disassembly of the engine.

Operation.—The engine as shown and described may operate with compression ignition in the manner well-known in opposed-piston engines, the spark ignition could be provided if desired. Air from blower units 79 is conducted thru conduits 77 to windchest 74, from which it is admitted to each of cylinders thru ports 54 in a swirling blast whenever ports 54 are uncovered by pistons 90, while the exhaust passes out thru ports 55, uncovered by the piston 40, thru elbows 25 to manifold 26. Pistons 40 and 90, approaching each other, compress the charge 75 of air, and at the right moment, a shot of fuel

is injected thru nozzle 59 by the fuel pump 39 and associated parts, and the resulting combustion drives pistons 40 and 90 outward again.

In an opposed-piston barrel engine, the resultant piston thrust is almost entirely outward, (the only possibility of an inward resultant being after mid-stroke on compression when piston inertia may exceed the compression pressure), but the outward thrusts of the opposing pistons are not balanced relative to the center of the engine, being considerably greater on the side where the pistons are at "top center" position. If the two engine mechanisms are fixed on the same shaft, as usually arranged, the unbalanced condition tends to bend the shaft; either the shaft must be made very rigid and strong to carry the bending load safely, or the shaft bearings must be able to support the shaft adequately against bending. This difficulty is avoided in the present invention by providing separate shafts 10 and 60 for the two engine mechanisms, mounting each shaft on adequate journal and thrust bearings, so that the bending load is transferred to the casing members which are naturally able to carry them. Slipper thrust bearings such as 12 and 62 may be used, and may be located either outwardly or inwardly from the respective engine mechanism.

Another important objective reached by this construction is the ability to adjust conveniently the phase relationship between the exhaust pistons and the intake pistons. Piston 40 should open the exhaust ports 55 to permit the cylinder pressure to drop to atmospheric before piston 90 opens intake ports 54, and it is also desirable that exhaust ports 55 close before intake ports 54 close to permit supercharging the cylinder to blower pressure. It is customary, therefore, in opposed-piston engines, to run the exhaust pistons somewhat in advance of the intake pistons, the optimum phase relationship being determined by trial.

The various engine accessories such as the oil and water pumps, and scavenging blowers 79, are not included in detail in the present invention. Some may be driven by radial drive shafts 19; others may be grouped in an easily removable accessory assembly 97 at the rear of the engine. If shaft 60 must drive the accessories and at the same time do its part in turning shaft 68, more power must be developed by the after reciprocating-rotary engine mechanism than by the forward one. This may be accomplished by making pistons 90 of greater diameter than pistons 40, cylinders 53 being of larger bore than cylinders 52. Other advantages of making the exhaust pistons smaller than the intake pistons have already been discussed.

Plain bearings between the working faces of swashplate members 13 and 63, and wabbler 30 and 80 respectively, can carry the thrust loads imposed upon them only by virtue of the progressive rotation of the maximum load area around the wabbler during operation, which action, combined with the freedom of the wabbler to rock on its spherical pilot, will tend to maintain wedge-film lubrication between the coacting plane surfaces. In view of the continuously unidirectional thrust load on the wabbler bearings in an opposed-piston barrel engine, pivoted slipper bearings are preferred, since they are able, as is well-known, to maintain the desired wedge-film lubrication of their working surfaces by tilting on their pivots. The "underslung" type of slipper illustrated is also free to rotate in its socket at will, promoting good lubrication of the socket and free tilting action. Flooded lubrication, with

the bearing elements operating in an oil bath, as provided in this invention, is practically essential to the success of either plain or slipper bearings in a wabbler mechanism.

5. With the particular type of piston-wabbler connections shown, the torque reaction appears as side thrust on the piston members. In the present invention, this side thrust is carried by shoes 42 or 92 directly to cylindrical guide surfaces 22 or 72 respectively, and piston members 40 and 90 are not subjected to any beam loading, the pistons proper serving only their primary function as surfaces 22 and 72 are easily and accurately machined in the casing members, and can be arranged coaxial with the cylinders without any difficulty. The spaces between the guide surfaces may be occupied by cooling fluid as indicated in the drawings, or could be used as conduits to transfer air from blower units 79 to windchest 74 if desired.

Having thus described the invention, it is clear that all the objects as stated herein have been attained. While I have shown particular structures, it is understood that changes in the arrangement and in the construction of the various parts may be made without departing from the spirit or scope of the invention as expressed in the following claims.

30. I claim:

1. In an opposed-piston barrel engine, a construction for the fixed parts of said engine comprising engine casing members, chambers in said casing members for the cooling fluid of said engine, individual cylinder members arranged parallel to each other and to the main axis of said engine and extending from one of said casing members to the other, annular water jackets on said individual cylinder members, said chambers in communication with and forming water manifolds for said annular water jackets, intake ports toward one end and exhaust ports toward the other end of each of said cylinder members said ports extending thru said annular water jackets with intervening axial water passages, a pressure chamber or windchest formed in one of said casing members and enclosing the intake port portions of said individual cylinder members and in common communication with said intake ports, and individual exhaust collectors enclosing and associated with the exhaust port portion of each of said individual cylinder members.

2. In an opposed-piston barrel engine, a shaft, individual cylinder members having cylinders parallel to said shaft, intake ports toward one end and exhaust ports toward the other end of each of said cylinders, two sets of pistons operably opposed in said cylinders the pistons of one set controlling the intake ports and the pistons of the other of said sets controlling the exhaust ports, operable connections between said pistons and said shaft, a pressure chamber or windchest enclosing the intake port portions of said individual cylinder members and in common communication with said intake ports, individual exhaust collectors each enclosing and associated with the exhaust port portion of one of said individual cylinder members to prevent the exhaust from one cylinder from blowing into the ports of adjacent cylinders, the exhaust port portions of said cylinders and the pistons controlling exhaust be-

ing of smaller diameter than the intake portions of said cylinders and their pistons in order to provide enough room between cylinders for said individual exhaust collectors while permitting maximum total displacement in the engine.

3. A construction for the fixed parts of an opposed-piston barrel engine comprising two similar engine casing members spaced apart, chambers in said casing members for the cooling fluid of said engine, individual cylinder members arranged parallel to each other and to the main axis of said engine and extending from one of said casing members to the other, annular jackets for cooling fluid on said individual cylinder members and connecting the said chamber of one of said casing members with the chamber of the other, intake ports toward one end and exhaust ports toward the other end of each of said cylinder members said ports extending thru said annular jackets with intervening port bridges having axial passages for the cooling fluid, a third casing member capable of forming the main supporting frame of the engine and extending from one of said similar casing members to the other and surrounding the intake portions of said cylinder members enclosing them in a common pressure chamber or windchest in common communication with said intake ports, and individual exhaust collectors each surrounding the exhaust port zone of one of said cylinder members.

4. A construction for the fixed parts of an opposed-piston barrel engine comprising two similar engine casing members spaced apart, chambers in said casing members for the cooling fluid of said engine, individual cylinder members arranged parallel to each other and to the main axis of said engine and extending from one of said casing members to the other, annular jackets for cooling fluid on said individual cylinder members and connecting the said chamber of one of said casing members with the chamber of the other, a third casing member extending from one of said similar casing members to the other and surrounding portions of said cylinder members and forming an oil-tight closure from one of said similar casing members to the other, and an expansion joint between two of said three casing members.

5. A construction for the fixed parts of a two-stroke barrel engine comprising engine casing members, individual cylinder members attached thereto, exhaust ports in said cylinder members, and individual exhaust elbows each surrounding the exhaust port portion of one of said cylinder members in a manner permitting said elbow to swivel slightly about said cylinder member.

6. A construction for the fixed parts of a two-stroke barrel engine comprising engine casing members, individual cylinder members extending from one of said casing members to another, exhaust ports in said cylinder members, individual exhaust elbows each surrounding the exhaust port portion of one of said cylinder members in a manner permitting said elbow to swivel slightly about said cylinder member, and a plane flanged outlet on each of said elbows, the flanged outlets of the several elbows being substantially in a common plane for convenient attachment to a common manifold.
